UNITED STATES PATENT OFFICE.

TERELIUS A. HILL AND JESSE PEELE, OF MARYVILLE, TENNESSEE.

QUILTING ATTACHMENT FOR SEWING-MACHINES.

SPECIFICATION forming part of Letters Patent No. 338,154, dated March 16, 1886.

Application filed August 11, 1885. Serial No. 174,109. (No model.)

To all whom it may concern:

Be it known that we, TERELIUS A. HILL and JESSE PEELE, citizens of the United States, residing at Maryville, in the county of Blount 5 and State of Tennessee, have invented certain new and useful Improvements in Quilting-Frame Attachments for Sewing-Machines; and we do declare the following to be a full, clear, and exact description of the invention, such as 10 will enable others skilled in the art to which it appertains to make and use the same, reference being had to the accompanying drawings, and to the letters and figures of reference marked thereon, which form a part of this specification. 15

This invention relates to certain new and useful improvements in quilting attachments for sewing-machines; and it consists in details of construction, arrangement, and combination of parts, as more fully hereinafter set forth and claimed.

The object of the invention is to devise a simple, cheap, durable, and portable track or frame to be readily attached to or removed 25 from the table of a sewing-machine, and made adjustable to various heights of tables by the inclination given to the upright supports.

A further object is to improve the construction of the carriage for carrying the material 30 to be quilted; and it consists in providing the same with a series of rolls arranged in a horizontal plane, the one receiving the quilted fabric being free to move vertically in its bearings, to adjust itself to the varying increase 35 of its diameter as the material is wound thereon, thereby keeping the material to be quilted always in a horizontal plane and on the machine-plate, while the roller extremely opposite to the one just described, and in the same 40 horizontal plane, carries the surfacing material, and at the same time is made to serve the purpose of a guide to give direction to the fabric and packing or wadding which is carried by a roller arranged on a higher plane 45 and in advance of the guide-roller, thus affording better facilities for keeping the fabrics and packing always even, and for detecting any folds or creases that may accidentally exist.

50 These objects we attain by the construction shown in the accompanying drawings, in which--

Figure 1 represents a plan view of a sewing-machine table having our attachment thereon. Fig. 2 is a side view elevation of the 55 carriage, with its near side removed to show the position of the rollers and the direction of the fabrics. Fig. 3 is an end elevation looking in the direction of the arrow, Fig. 2. Fig. 4 is a perspective view of the track or frame. 60

The machine-table A has attached thereto the frame C, on which runs or traverses the carriage D. The frame C is made of two corresponding parts, each consisting of a rectangular frame, C', provided with supports hinged 65 to their outer ends, and clamps E on their inner ends, which clamps consist of a metallic plate, e, secured to the upper surface of the side bars of the sections C', and a spring-plate, e, secured to their under side by a 70 thumb-screw, F. The sections C' are held together by a bar, G, secured thereto by set-screws g.

The frame C is secured to a machine-table 75 by the clamps E, and is supported by the legs e, which are inclined to the machine to suit tables of different heights. This frame when detached can be stowed in small compass, as the legs fold on the sections and the sections can be placed one on the other. The plates e 80 of the clamps are flush with the face of the side bars of the sections C', and extend to within a short distance of each other when the frame is in place, to form a nearly uninterrupted track on which the carriage D traverses, the ends of said plates being beveled to avoid giving any sudden jolt to the carriage 85 in its passage over the gap between the plates.

The carriage D consists of side plates, H, braced by transverse bars h h', and carries 90 rollers I I' I". Flanged rollers J, suitably secured to the side plates of the carriage, are designed to run on the track and relieve the friction.

In practice, the frame C being adjusted and 95 the carriage being provided with the fabrics to be quilted, the roller I carrying the under fabric and the wadding, and the roller I' carrying the other or upper fabric, said carriage is placed on the track, the roller I" extending 100 beneath the arm B of the machine, which latter being set in motion the carriage is fed transversely and the fabrics quilted. An elastic band or strap, K, is attached to the side of

the carriage, and is designed to be attached to the fabrics, to prevent the same gathering or tucking while being quilted, while an elastic finger, L, serves as a marker, and to keep the 5 fabrics down on the machine-table at their forward or initial edge. The spring or elastic finger L possesses sufficient rigidity to press on the fabrics at their forward or initial edge to keep them down on the table, while at the same 10 time it yields to and permits different thicknesses of stuff to pass beneath the same without raising the carriage off the track, which would be the case if the bar were non-yielding. After one line of quilting, the carriage is 15 returned to its normal or starting position, the set-screws M of the threaded journals N of the various rollers are slackened, the fabrics fed forward the proper distance for the next stitching, and the set-screws tightened, when the 20 device is in readiness for the next operation.

It will be noticed that the roller I", around which the quilted fabric is wound, is journaled in slots i in the sides of the carriage. This is 25 important, as the bulk of the roller gradually increases at each winding, and it permits the same to rise so as to keep the fabric in a horizontal position. An elastic strap, O, passes over each of said slots i, to prevent the accidental displacement of the roller I". One end 30 of the straps is fixedly secured to the sides beyond the slots, while the other end is provided with an eyelet, o, to enter one of a series of openings, o', in the ends of the sides H of the carriage, to allow for the slack or give of the 35 straps.

By making the straps O of elastic material the roller I" may be removed or replaced without freeing either end of the straps, and provision is made for the journals of the roller to 40 rise above the level of the top edge of the sides

H of the carriage. The tension on these straps may be regulated by adjusting the eyelets into one or the other of the openings o'.

Having thus described our invention, what we claim, and desire to secure by Letters Patent, is—

1. In a quilting attachment for sewing-machines, the combination of a frame made in corresponding sections, each provided with a hinged support at one end and a clamp at the other or adjacent end, consisting of plates extending flush with the upper face of the sections to extend across the machine-table and form a nearly continuous track, and spring-plates secured to the under side of said sections by screws, substantially as set forth, and a bar to hold the sections together, as shown and described. 55

2. In a quilting attachment for sewing-machines, the combination of a carriage provided with rollers carrying the fabrics to be quilted, of a take-up roller mounted in vertical slots, and elastic bands, as O, rigidly secured at one side of the slots, over which they extend, and adjustably secured at their outer ends, substantially as shown, and for the purpose described. 60

3. The combination, with a carriage, for the purpose herein set forth, of an elastic band or strap, K, and a spring marking-finger attached to the forward or initial side of the carriage, substantially as shown, and for the purposes specified. 65

In testimony whereof we affix our signatures in presence of two witnesses.

TERELIUS A. HILL.
JESSE PEELE.
